UNITED STATES PATENT OFFICE.

WARREN R. WALKER, OF BLOOMFIELD, NEW JERSEY, ASSIGNOR TO COOPER HEWITT ELECTRIC COMPANY, OF HOBOKEN, NEW JERSEY, A CORPORATION OF NEW JERSEY.

ELECTRIC SWITCH.

Application filed February 15, 1926. Serial No. 88,392.

The present invention relates to electric switches of the liquid flow type and particularly to mercury switches. The invention further relates to switches of this type having a sealed envelope into which are sealed electrodes between which current path is made and broken by the movement of the mercury with relation to the other parts of the switch, and in which a wall or septum which has a passageway therethrough is positioned across the envelope preferably between the electrodes therein and which is utilized for separating mercury in the switch into more than one part in the open circuit position thereof and which permits joining of the said parts of mercury through the passageway thereof in the closed position of the switch, said septum being of special arc resisting material and preferably having the wall of the switch fused thereto. The invention further relates to a switch of this type having an envelope of comparatively cheap glass fused or laid down on to a septum which is separate therefrom and which is made of a material highly resistant to electric arcing.

Switches of this type are adapted for making and breaking circuit therethrough, either by rotation of the switch about an axis extending substantially normally through the septum, or by tilting of the switch in a plane of that axis.

Various other objects and advantages of the invention will be obvious from the following particular description of embodiments of my invention or from an inspection of the accompanying drawing; and the invention also consists in certain new and novel features of construction and combinations of parts hereinafter set forth and claimed.

In the following description and in the claims parts will be identified by specific names for convenience of expression, but they are intended to be as generic in their application to similar parts as the art will permit.

In the accompanying drawing are shown for purposes of illustration one form of mechanism with certain modifications there-of embodying the invention, in which

Fig. 1 is a longitudinal sectional view of an embodiment of the switch of my invention showing a sealed envelope having mercury therein and electrodes sealed thereinto

from either end each of which has a downward extension for contact with the mercury, and a septum provided with an aperture through which in closed circuit positions of the switch the mercury extends for making contact between said electrodes, the wall of the envelope being fused down onto the edges of the septum to hold it in place and to provide a tight joint therebetween.

Fig. 2 is a transverse sectional view of the device of Fig. 1 taken along the line 2—2 and looking in the direction of the arrows in that figure,

Fig. 3 is a longitudinal sectional view of an alternative embodiment of my invention showing electrode extensions which extend around the interior of the envelope, and showing the switch in the open circuit position,

Fig. 4 is a sectional view of the device of Fig. 3 taken along line 4—4 and looking in the direction of the arrows, but with the switch in the closed circuit position,

Fig. 5 is a face view of an alternative form of septum having two perforations there-through diametrically spaced,

Fig. 6 shows an alternative embodiment of the septum having one perforation which is extended arcuately for permitting the closing of the circuit during the predetermined period of time while the switch is rotating on its axis at a predetermined rate of speed and likewise be made to have the circuit open therethrough for a corresponding predetermined period of time,

Fig. 7 shows a septum having a simple perforation therethrough at one position and an arcuate perforation at another whereby the rotation of the switch in which the septum is embodied circuit may be established alternately for different periods of time when such rotation is made at a given rate of speed,

Fig. 8 shows a septum having two arcuate openings diametrically spaced whereby a similar result is produced as with the septum of Fig. 6 but in which the open circuit periods are shorter with respect to the closed circuit periods.

In Figs. 1 and 2 of the drawing the envelope 1 preferably of boro-silicate glass such as G702P glass carries sealed therethrough on each end electrode leads 2 and 3 which extend inwardly toward each other

and are axially aligned. Each of the leads 2 and 3 carries an electrode 5 connected thereto which extends toward the envelope wall which contact with the body of mercury 6 in the envelope. A septum 7 of porcelain having a thermal co-efficient of linear expansion at or near that of the glass of the envelope extends entirely across the sides between the walls of the envelope 1 10 and is held in place by having the wall of the envelope fused down thereonto about edges thereof. Between its point of support and its edge said septum 7 has formed therethrough a perforation 8 for the flow of mercury to connect in the closed circuit position of the switch two pools into which the mercury is formed on either side of the septum 7.

In the operation of this embodiment of my invention the switch is rotated on its axis to bring said perforation 8 below or above the level of the mercury 6 for making and breaking of a current path therethrough. In its operation as a simple switch it can be rotated backward and forward to a small part to bring said opening 8 below or above the surface of the mercury as desired. In operating the device as a time switch it is rotated continuously at a predetermined rate of speed whereby the septum in travelling from its point of emerging from the mercury to its points of immersion therein occupies the predetermined period of time and likewise the movement of the opening from this point of immersion into its point of emerging from the mercury occupies the corresponding period of time, the time periods of the making and breaking of the circuit being recorded by the speed of rotation of the device. For obtaining the making of a circuit through the device at shorter intervals than that possible with the device of Fig. 1 with respect to the time periods of the opening of the circuit a septum such as shown in Fig. 5, is used where a plurality of perforations 9—9 are formed. These may be either diametrically spaced or otherwise equally spaced or they may be spaced at unequal angular distances about the center of the septum and center of rotation whereby different periods of make and break may be obtained as desired. In Fig. 6, for example, is shown the single perforation formed in the shape of an arc whereby at a given rate of speed of rotation the period of circuit make is lengthened and the period of circuit break is shortened. In Fig. 7 is shown a septum having a small perforation 9 at one point and a larger and arcuate perforation 10 at another portion whereby is obtained through the rotation of the switch intermittent periods of circuit make which are unequal in duration. And in Fig. 8 is shown two equally spaced arcuate perforations 10 in the septum 7.

The device of Figs. 1 and 3 may also be operated by tilting in which operation the perforation 8 is left in its position shown in Figs. 1 and 2 or brought to a point at a lesser depth in the mercury as desired according to the current broken and as to whether a time interval is to be injected into operation of the switch.

In Figs. 3 and 4 is shown a switch similar to that of Figs. 1 and 2 with exception that electrodes 5', 5' mounted on electrode leads 2 and 3 extended circumferentially around the interior of the envelope and at short distance therefrom whereby during the rotation of the switch for making and breaking circuit therethrough a section of each of the electrodes is at all times immersed in mercury 6 and any possible arcing between these electrodes in the mercury is precluded.

The envelope of this switch is preferably made of a glass, for example, a boro-silicate glass, the glasses generally known in the trade as Pyrex glass and G702P glass being particularly suitable for this purpose. For the septum a ceramic material is used which has a thermal co-efficient of linear expansion substantially the same as that of the glass. Materials which have co-efficients of expansion at or near those of G702P glass for example, are porcelains known in the trade as Fireite, which has a co-efficient of expansion of 0.00000354, Coors porcelain with a co-efficient of expansion of 0.0000034, and Elemite porcelain which has the same co-efficient of expansion as G702P glass.

As in other switches, an atmosphere of hydrogen or other gas is included in the switch envelope to serve to quench arcs formed during operation of the switch and to conduct heat from the interior to the walls thereof.

I claim:

1. In an electric switch of the mercury flow type, a sealed envelope of glass, electrodes sealed into the envelope, mercury in the envelope, and a septum of arc resisting material positioned across the envelope in the line of flow of mercury therein for opening and closing a circuit therethrough, the wall of said envelope being fused down against said septum, and said septum being formed with a passageway for the mercury.

2. In an electric switch of the mercury flow type, a sealed envelope of glass, electrodes sealed into the envelope, mercury in the envelope, and a septum of ceramic material positioned across the envelope in the line of flow of mercury therein for opening and closing a circuit therethrough, the wall of said envelope being fused down against said septum, and said septum being formed with a passageway for the mercury.

3. In an electric switch of the mercury flow type, a sealed envelope of glass, electrodes sealed into the envelope, mercury in

- the envelope, and a septum of arc resisting material having a thermal co-efficient of expansion substantially that of said glass positioned across the envelope in the line of flow 5 of mercury therein for opening and closing a circuit therethrough, the wall of said envelope being fused down against said septum, and said septum being formed with a passageway for the mercury.
- 10 4. In an electric switch of the mercury flow type, a sealed envelope of glass, electrodes sealed into the envelope, mercury in the envelope, and a septum of ceramic material having a thermal co-efficient of expansion 15 substantially that of said glass positioned across the envelope in the line of flow of mercury therein for opening and closing a circuit therethrough, the wall of said envelope being fused down against said septum, and said septum being formed with a passageway for the mercury.
- 10 5. In an electric switch of the mercury flow type, a sealed envelope of glass, electrodes sealed into the envelope, mercury in the envelope, and a septum of porcelain having a thermal co-efficient of expansion 20 substantially that of said glass positioned across the envelope in the line of flow of mercury therein for opening and closing a circuit
- therethrough, the wall of said envelope being fused down against said septum and said septum being formed with a passageway for the mercury.
6. In an electric switch of the mercury flow type, a sealed envelope of boro-silicate 35 glass, electrodes sealed into the envelope, mercury in the envelope, and a septum of ceramic material positioned across the envelope in the line of flow of mercury therein for opening and closing a circuit therethrough, the wall of said envelope being fused down against said septum, and said septum being formed with a passageway for the mercury.
7. In an electric switch of the mercury flow type, a sealed envelope of boro-silicate 40 glass, electrodes sealed into the envelope, mercury in the envelope, and a septum of porcelain positioned across the envelope in the line of flow of mercury therein for opening and closing a circuit therethrough, the wall of said envelope being fused down against said septum and said septum being formed with a passageway for the mercury.

Signed at Hoboken, in the county of Hudson and State of New Jersey, this 9th day of February A. D. 1926.

WARREN R. WALKER.
